UNITED STATES PATENT OFFICE

GEORGE GRINLEY SHARPE, OF ULCOMBE, ENGLAND, ASSIGNOR TO THE GOVERNOR AND COMPANY OF ADVENTURERS OF ENGLAND TRADING INTO HUDSON'S BAY, OF LONDON, ENGLAND, A BRITISH COMPANY

MEANS FOR STRETCHING RABBIT AND OTHER SKINS

Application filed May 31, 1928, Serial No. 281,885, and in Great Britain August 9, 1927.

This invention consists in an improved method of and means for stretching by tension rabbit or other skins. Hitherto, it has been customary to stretch such a skin by placing the skin on a board or frame of wood or other suitable material, and by applying by hand, or by an appropriate device or tool, tension to the marginal portions of the skin, and while a stretching operation is being carried out and those portions are under tension or are being pulled to nail those portions to the board. Sometimes a frame has been used for stretching a skin by attaching or connecting marginal portions of the skin to the frame by means of cords passing through rings fitted to the frame and through hooks that are detachably hooked to the skin, the cords serving to lace the frame and the skin together.

In carrying out in practice the present invention, a frame, formed of metal or other suitable material, is provided, which frame may be of a size to accommodate one or more skins at a time during a stretching period or operation, said frame comprising a pair of side members, a top member and a bottom member arranged to encompass a space. The top and side members are rigidly or detachably joined together in any convenient manner, for instance by means of an eye and pin connection or as in a picture frame. The bottom member is movable longitudinally of the side members and the side members are each provided with a number of pegs, pins or other pointed devices on which some of the marginal portions of a skin or of a number of skins are impaled during a stretching operation. The skins are connected adjacent their lower margins to the bottom member of the frame by hook-like members of which the opposite ends detachably engage the skins and the bottom member of the frame. The skins impaled on said pegs and hook-like members are thus held in the stretched condition on the frame. The pegs are arranged at any suitable inclination to faces of the frame and at any desired distances apart.

The frame is preferably of an upright character with the lower and upper ends of

its side members attached, respectively, to feet or bases and to the top member.

If the frame be of a size adapted to accommodate more than a single skin during a stretching operation and be such that while one or more marginal portions of a skin can be thus impaled other marginal portions cannot be impaled but remain free or disconnected, these latter portions may be attached to free marginal portions of other skins by means of separate hooking devices which have terminal parts so formed or shaped that they can be readily hooked to adjacent skins and be unhooked when required.

The hooking devices may consist of a single integral part or member, or of a number of parts, for example of two aligned end members connected together by means of a coil spring or other resilient element in line with the end members. Alternatively, the spring and the two end members of the hook may be formed in one piece.

The invention is illustrated in the annexed drawings, in which:—

Fig. 1 is a front elevation of the device showing four skins in a stretched position, and

Figs. 2 and 3 are detail views showing two different types of hooking devices.

The frame on which the skins *a* are stretched is formed of two uprights *b* and *b'* and two horizontal members *c* and *c'*. The members *b*, *b'* are provided with foot members *d*. The lower horizontal member *c'* is preferably adapted to be vertically displaced longitudinally of the lower portions of the members *b*, *b'*, in order to accommodate itself to variations in the vertical dimensions of the lower of the two rows in which the skins are conveniently arranged. The two vertical members *b*, *b'* and the horizontal member *c* are each provided with a plurality of pegs or pins *e*, suitably spaced apart, and serving to hold the marginal portions of a skin in position after the latter has been stretched.

In order to hold the adjacent marginal portions of two neighbouring skins in position a plurality of hooking devices, suitably spaced apart, is employed. The free verti-

- cal marginal portions may be held in position by hook members which comprise two similar hook portions *f* connected together by an interposed spring *g* by means of which tension is applied to the skins. The free adjacent horizontal marginal portions of two skins may be held in place by means of the hook members *h* which are formed with a barb at each end connected by a straight portion.
- 5 10 The lower edges of the lower row of skins may be connected to the member *c'* by hooks similar to the members *h*.

Having thus described the nature of the said invention and the best means I know of 15 carrying the same into practical effect, I claim:—

1. A device for stretching skins of animals, comprising a vertical frame including a pair of side members, a top member connecting 20 said vertical members adjacent their upper ends, a bottom member movable relatively to said top member, skin-engaging members carried by said side and top members, and skin-engaging hooks detachably mounted on 25 said bottom member.

2. A device for stretching skins of animals, comprising a vertical frame including a pair of side members, a top member connecting 30 said side members adjacent their upper ends, a bottom member having its end slidable longitudinally of side members, skin-engaging means carried by each of said side and top members and skin-engaging hooks detachably mounted on said bottom member.

35 In testimony whereof I have signed my name to this specification.

GEORGE GRINLEY SHARPE. [L.S.]
